Patented Dec. 6, 1921.

UNITED STATES PATENT OFFICE.

ANTON HULSMANN, OF SAN FRANCISCO, CALIFORNIA.

ARTIFICIAL-ARM FRAME.

1,399,622.

Specification of Letters Patent.

Patented Dec. 6, 1921.

Application filed July 15, 1921. Serial No. 485,006.

To all whom it may concern:

Be it known that I, ANTON HULSMANN, a citizen of Germany, residing at San Francisco, in the county of San Francisco and State of California, have invented new and useful Improvements in Artificial-Arm Frames, of which the following is a specification.

This invention relates to a frame for artificial limbs especially artificial arms and has for its primary object to provide a frame of this character which may be manufactured in less time than heretofore necessary in producing devices of this kind and with a consequent saving in labor and production cost in every particular.

A further object of my invention is to produce an arm frame in which the side arms and stump cover are made from a single piece of sheet metal thus doing away with all useless connections and joints which not only add to the cost price of the frame but result in inconvenience to the wearer.

Still another object of this invention is to produce a light yet exceedingly strong and efficient frame which will meet all requirements of the user.

Other objects and advantages will be apparent during the course of the following description.

In the accompanying drawings forming a part of this specification and in which like numerals are employed to designate like parts throughout the same,

Figure 1 is a view in perspective of the frame parts assembled,

Fig. 2 is a plan view of one of the upper side members,

Fig. 3 is a detail view taken on the line 3—3 of Fig. 2 showing the blank in Fig. 2 bent upon itself to produce the relatively narrow upper side member,

Fig. 4 is a view in plan of the blank from which the fore arm member of the frame is made, and

Fig. 5 is the die for bending or forming the stump cover of the fore arm frame.

In the accompanying drawings wherein for the purpose of illustration is shown a preferred embodiment of my invention, the numeral 1 designates a blank which is first cut or stamped from sheet metal to leave a semi-circular part 2 intermediate the ends 3 of the strips 4 and 5. The part 2 is provided with an eye 6 and the ends 3 are like-

wise made with eyes 7 and also with a slight shoulder 8 made by leaving an excessive width of metal for the ends.

This blank 1 after being cut as just described is introduced into a die press 9 with a pin 10 of the die engaging the eye 6 so as to center the part 2 whereupon applied pressure to the die will press the part 2 of the blank into a cup shaped stump cover as shown at 2^a in Fig. 1. The strips 4 and 5 being bent upwardly to leave the fore arm members 4^a and 5^a and with the eyes 7 in the ends 3 made to receive the headed pins 11 and 12 which pivotally connect the upper side members 13 and 14 to the fore arm members 4^a and 5^a the latter being made preferably as follows:

As shown in Fig. 2 a relatively wide blank 15 of the desired length is cut from sheet metal the same being cut wider at its base 16 in which the two openings 17 are made, than at its top 18. After being thus cut and with the openings 17 made it is bent along a medial line as shown by the dotted line 19 so that the strip may be folded upon itself to leave a double thickness for the upper side members 13 and 14. A suitable bending or folding device is used in this operation so that the ends 20 of the members 13 and 14 include pockets to receive the ends 3 of the fore arm members 4^a and 5^a so that the eyes 7 therein and the eyes made by the openings 17 may register to receive the head pins 11 and 12 in pivotally connecting the two sets of members together. In making these pockets the inside folds of each member continues straight but the outside folds are bent slightly outward as at 21 and then downwardly in space relation from the outside folds.

It can be seen from the above how easily and cheaply the frame may be made and how efficient it will work out in practice compared to those devices which have heretofore been used.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described my invention, I claim:

1. In an artificial arm frame, fore arm

side members produced from a single strip of material and including an integral stump cover, and upper side members pivotally connected to ends of the fore arm side members, said upper side members being produced from separate sheet metal blanks each folded upon itself to produce a double thickness of metal for each member.

5 2. In an artificial arm frame, fore arm side members produced from a single strip of material and including an integral stump cover, and upper side members pivotally connected to ends of the fore arm side mem-

bers, said upper side members being produced from separate sheet metal blanks each 15 folded upon itself to produce a double thickness of metal for each member, and with the outside folds of each member bent outwardly and then downwardly in respect to their inside folds to leave pockets between 20 the folds to receive the ends of the fore arm side members substantially as and for the purpose described.

In testimony whereof I affix my signature.

ANTON HULSMANN.
